UNITED STATES PATENT OFFICE.

EDWARD E. CLEMENT, OF WASHINGTON, DISTRICT OF COLUMBIA.

METHOD OF ESTABLISHING VARIABLE CONDUCTIVE PATHS FOR ELECTRICAL COMMUNICATION.

1,103,898.

Specification of Letters Patent. Patented July 14, 1914.

Application filed March 14, 1912. Serial No. 683,799.

To all whom it may concern:

Be it known that I, EDWARD E. CLEMENT, a citizen of the United States, residing at Washington, in the District of Columbia, have invented certain new and useful Improvements in Methods of Establishing Variable Conductive Paths for Electrical Communication, of which the following is a specification, reference being had therein

10 to the accompanying drawing.

My invention relates to the art of electrical transmission of intelligence over wires.

It has for its object the improvement of methods for establishing variable conductive paths for such transmission, with special reference, as herein presented, to the handling of telephone traffic. Such methods may be very briefly stated as follows: (a) According to the manual method uni-

versally employed, all traffic is arbitrarily divided into portions allotted and directed to operators having a fixed and definite capacity only, each subdivided portion of the total traffic moreover being subject to arbitrary fluctuations in its own volume, without reference to any other portions, and being also affected by any general causes of fluctuation in the total volume; each operator upon receiving a traffic unit, is forced

25 to perform a number of detail steps, varying somewhat according to conditions, and as these steps are repeated for every unit, the summatic result is that the maximum volume of traffic handled by one operator in a given period, as well as the average time per unit during that period, is limited by the speed with which the several steps or operations required can be performed. These steps include every detail of results required

30 by good practice. Inasmuch as the predetermined volume of traffic or work assigned to each operator is subject to casual variations which may or may not affect the main volume of traffic in the exchange, as well as the regular diurnal variations recognized in all systems, it is necessary not only to subdivide the traffic or work with reference to probable maximums or peaks, but also to assume and arbitrarily fix a permissible maximum for the operator time per unit. More

35 specifically stated this means that where the number of calls per line on any given operator's position is subject to large fluctuation, the number of lines in the allotment must be determined with respect to the possible

maximum of calls to be handled at that position, assuming the maximum waiting time. Disregarding the question of apparatus entirely (because the method is practised with many diverse forms of apparatus), it must be apparent that this method is extremely inefficient. (b) According to the so-called automatic method, the steps in operation for handling a traffic unit as specified under (a) are performed by mechanism, and this mechanism is guided and directed by certain steps performed by the subscriber instead of by the operator. The question of subdivision of traffic among operators is thus eliminated, because the traffic handled by each subscriber is only that originating with himself, and is limited by his own capacity for operating. The question of subdivision of traffic among operating machines in the exchange remains however, and the losses in efficiency due to arbitrary subdivision are still the same.

According to the present method, the total traffic is not arbitrarily subdivided as to definite portions thereof among specific operators, but is distributed with uniformity among all the operators, and in order to remove the limitation of operator time per unit in fixing maximums, the operator is not required to specifically perform the necessary steps in disposing of each traffic unit, but is required only to predetermine the final disposition of the unit by performing a single act in two correlated motions, the time for which is practically a constant. Thus not only are the possible maximum of volume per operator largely increased and the required operator time per unit reduced, but owing to the uniformity of distribution of load, the necessity for an arbitrary maximum waiting time is eliminated and the general efficiency thereby enormously increased. The limit of distribution among the operators is flexible, and is arranged to be varied as the variations in the summatic traffic volume, or in other words, the number of operators on duty and included in the uniform distribution of traffic, is varied in accordance with the variations in the load curve.

More specifically stated, this method contemplates converging calls, when initiated, upon and distributing said calls among, correlated interchangeable connective mechanisms such as connective trunks and the

switches, distributing and referring the calls at this stage through correlated interchangeable normally free secondary mechanisms, such as operators' trunks and switches, to 5 and among the operators, then having the operators ascertain in each case the nature and destination of the call, that is to say the class of call and the number wanted, then causing the operators to set up or predetermine the whole expression of the designation 10 of said destination in a code form, as for example by pressing down a number of code push buttons, and finally relieving the operators of any further duties and causing the 15 operations of the connective mechanisms to proceed in accordance with the predetermined code form.

Stated in terms of the apparatus, the calls are converged upon and distributed among 20 connective trunks by means of primary selectors, then they are distributed and referred through correlated secondary selectors and separate operators' trunks to idle operators' positions, then the operators ascertain 25 the class of calls and numbers wanted, and for each call press buttons or set up equivalent devices to indicate the whole number wanted, and if necessary the class of the call; and finally, the operation of the connective mechanisms or selective switches is 30 brought about in accordance with this predetermination without further volition or attention on the part of the operators. It will be noted that a salient feature of this operation 35 is the concentration of all operator's duties into one mental act, resulting in one brief physical act or series of acts, *i. e.* pressing the buttons. The further operations growing out of this mental act may be said 40 to be latent while the operator is determining in unitary code form all the subsequent steps in operation of the connective agencies or mechanisms.

This method can be practised with a variety 45 of apparatus and circuits, including the apparatus and circuits described and claimed in a large number of my prior pending applications in which the method is incidentally disclosed, and particularly the following: Serial No. 306,292, filed March 15, 1906; Serial No. 323,096, filed June 23, 1906; Serial No. 327,096, filed July 20, 1906; and Serial No. 345,167, filed November 26, 1906. The description of apparatus and circuits herein is limited to the disclosures in 50 the applications thus identified, the illustrations being taken particularly from applications Serial No. 323,096, filed June 23, 1906 and Serial No. 327,096, filed July 20, 1906.

My invention is illustrated as to two forms of apparatus with which it may be practised, in the accompanying drawings in which—

Figure 1 shows subscribers' stations and 65 lines. Figs. 2, 3 and 4 show portions of

three primary selector sets. Fig. 5 shows a set of signaling buttons and an impulse generator to work in connection with Fig. 6. Fig. 6 shows a trunk circuit with a secondary set of relays which are normally disconnected from it. Fig. 7 shows automatic switch circuits. Fig. 8 is a modification of Fig. 6 and works in conjunction with Fig. 7. Fig. 9 shows apparatus equivalent to that of Fig. 5 but adapted to operate in connection with Figs. 8 and 7. In this figure the toothed number wheels are driven from a power shaft and the connection between the wheels and the shaft is made by a mechanically controlled clutch. Fig. 10 is a condensed diagram of a primary selector set. Figs. 11 and 12 are respectively a side and top plan view of a ten point relay used in my system. Fig. 13 is a plan view showing a strip of keys or buttons containing two signal lamps. Fig. 14 is a plan view showing the slide which controls or latches the various buttons. Fig. 15 is a sectional view of a portion of one of the strips of buttons. Fig. 16 is an end view showing the buttons mounted on an inclined support or cabinet. Fig. 17 is a transverse sectional view showing a strip of ten buttons. Fig. 18 is a top plan view of Fig. 16 showing the arrangement of the various sets of buttons, there being one of these equipments for each operator. Fig. 19 is a diagram showing switches instead of relays for primary and secondary selector sets. Fig. 20 is a diagram complementary to Fig. 19, showing an operator's key set and sending machine. Fig. 21 is a skeleton diagram showing a number of subscribers' stations, a central office equipment having primary and secondary selectors only, each secondary selector being appropriated to one operator's key set, subscribers' lines being shown multiplied into both the primary selectors and the operating or selective automatic switches. Fig. 22 reproduces a portion of the trunk 30—31 of Fig. 6 and shows also the corresponding portions of trunks 130—131 and 230—231, to illustrate the relation existing between the trunks, whereby one trunk always is held in readiness to respond to a call instituted by a telephone line. Fig. 23 reproduces the secondary selector equipment of Fig. 6 in duplicate, showing the relation between the operators' equipments and the trunk circuits whereby an active trunk will select and connect with an idle operator's equipment.

Before proceeding to the circuits, it will be advisable to obtain a clear understanding of the types of apparatus employed herein, and which are shown in Figs. 9 to 18, inclusive. There is no special illustration of the ordinary or single point relay, which is sufficiently familiar to everyone skilled in the art. The circuits shown in Figs. 2, 3 and 4 constitute the primary selector or

answering portion of the equipment. In this appear a number of ten point relays and a number of single point relays. The only special feature required in the latter is some form of locking means, shown in the form of extra windings for maintaining energization. At the subscribers' stations there is no special apparatus, the ordinary common battery telephone equipment being employed.

Referring to Figs. 11 and 12, I will briefly describe the ten point relay, N. This comprises an iron back yoke, n , a pair of magnets, n' , mounted thereon, an armature n^2 , 5 extending across the front end thereof, and a set of contact-springs, n^3 , n^4 , n^5 , n^6 , overlying the upper bell-crank extension of the armature, so as to be worked thereby. There are eleven sets of these springs, all secured 10 at the rear end of the relay upon the return member, n^7 , of the back yoke. The front ends or pole pieces of the cores of the electromagnets, n' , receive the front yoke, n^8 , of non-magnetic material, such as brass, this 15 also having an upper return portion, n^9 , overlying the magnet windings, and aligned with the return portion, n^7 , of the back yoke, n . Upon this return portion, n^9 , of the front yoke the upper bell-crank arm, 20 n^{12} , of the armature, n^2 , lies flat under normal conditions. Cut from end to end of this upper bell-crank portion, n^{12} , are two grooves in which rest the insulating studs of the spring sets. The function of these 25 slots with the studs resting in them is to retain the armature in place. At their front ends the springs are separated by shouldered studs, the lowermost stud of each pair resting upon the armature, carrying the lower 30 spring of its pair, n^6 , on its shoulder, and the upper spring, n^5 , on its head, its stem passing through a hole in the spring, n^6 , while the uppermost stud of each pair rests upon the spring, n^5 , supports the spring, n^4 , 35 upon its shoulder, and carries the spring, n^3 , on its head, its stem passing through a hole in the spring, n^4 . The actuating studs affect only the springs, n^4 , n^6 , of each set, these 40 constituting the movable springs, while the others, n^3 , n^5 , are fixed. Each actuating stud carries the spring, n^6 , on its shoulder, and the spring, n^4 , on its head, its stem passing 45 through holes in the springs, n^5 , n^6 .

The entire relay is secured to an insulating back block, n^{10} , by means of the bolts, n^{11} , constituting extensions of the cores and threaded to receive lock-nuts. The rear ends of the contact-springs extend out through openings made in this block, and an inclosing shell or casing, n^{13} , is fitted to the block, with which it forms a tight joint all around the edge. This shell is secured in place by means of the stud, n^{14} , threaded to receive the nuts, n^{15} .

As the armature n^2 , is attracted, the

springs, n^4 , n^6 , are lifted by the actuating stud, until their outer points make contact with the corresponding points of the springs, n^3 , n^5 , in each set. Ten of these sets are line-contacts, and the eleventh is for locking purposes, as will sufficiently appear from the description of the circuits.

The same structure of relay frame is used for these relays as for those relays in the primary selector wherein it is desired to break a number of circuits, as for instance in the relay D^x of Fig. 6. In such an instance, the shoulder studs are cut to support springs n^4 , n^6 and the actuating studs are adapted to lift springs n^3 , n^5 away from springs n^4 , n^6 respectively.

The switches which I preferably employ herein, and which are referred to in the preamble as connective apparatus, may conveniently be the standard Strowger automatic switches, such as shown in the patents to Keith and Erickson, #815,176 and #815,321, dated November 13th, 1906. No further description of these switches is necessary therefore. Any specific differences between the present specifications and those of the patents referred to will sufficiently appear from the statement of operation.

The next piece of apparatus requiring attention is the operator's impulse transmitter or key set, which is shown in Figs. 13 to 18 inclusive. Referring to Figs. 13, 14, 15 and 17, the construction of these key sets is very plainly shown. The contact springs 95 73, 790, and the lamp jack springs k^9 and k^{10} are mounted in a rubber block k^{21} which is attached rigidly to the plate k^{12} by means of the screws k^{11} passing through a clamping strip k^8 and screwed into the plate k^{12} . The two strips k^3 and k^2 are also rigidly fastened to this plate by means of small screws or rivets. These two strips are provided with the ribs k^{13} which form the bearing for the slide k' . This slide is provided with clearance holes k^{15} , plainly shown in Fig. 14. The slide is kept in its normal position toward the left by the tension spring k^{14} which is mounted in a manner similar to that of the contact springs. The strips k^3 and k^2 are also provided with openings 100 which lie directly in line with those of the slide k' . These holes or openings are fitted with the buttons K which consist each of the rubber plunger head k which is fastened to the rod k^{40} . This rod contains the metal cone k^6 which can be a separate piece or a portion of the rod k^{40} . The heads of the buttons k^{30} are attached to the rod in the same manner as the plunger ends and are kept in a locked position by means of the lock nut k^5 . Referring to Fig. 15, when one of these buttons is depressed the cone k^6 passes through the opening in the slide k' , and the slide under tension of the spring k^{14} 105 is caused to ride over and hold the cone in 110 115 120 125 130

its downward position. The button is kept in this indicating or locked position until some other button in the same strip is depressed. The button is then released as soon as the edge of the cone of the button which is being depressed enters the opening in the slide k^7 . The buttons are forced up or returned to their normal position by means of the contact springs 790 riding on the cone portion of the rubber plunger. When a button is depressed the contact springs 73 and 790 are connected.

Referring to Fig. 13 the listening button K^x when depressed closes the contacts of two sets of springs so as to enable the operator to bridge her talking set across the trunk. This button, as well as that of the starting button, K^x , is not provided with the cone k^6 , as they are not to be kept in a locked position or restore any of the buttons in the set. The lamps L and L' are separated by a strip k^8 so as to prevent the lighting of one causing the bull's-eye of the other to be illuminated.

Referring to Fig. 17, I have shown a full strip of ten buttons the operation and construction of which is the same as that of the four buttons shown in Fig. 13. All of the buttons in Fig. 17 are arranged so as to release one another.

Referring to Figs. 16 and 18, I have shown the arrangement of the buttons for one operator's position where the capacity of the exchange is ten thousand lines and where provision is made for 4-party selective ringing.

Referring to Fig. 18, the first row of buttons, K' , represent the thousands digit; the second row, K^2 , the hundreds digit; the third row, K^3 , the tens digit; the fourth row, K^4 , the units digit; the fifth row, K^5 , contains the four selective ringing buttons, the two signal lamps, and a listening and a starting button. The operator is provided with three of these sets as shown. If the first set is busy the next idle set will come in use and so on. To distinguish the various sets and form dividing lines I use different colored buttons; for instance, the buttons of the first row are white, the second black, the third white, the fourth black, and the fifth red.

The cabinet or frame, k^{20} , on which these keys are mounted is of pressed metal and in appearance greatly resembles an adding machine. These cabinets can be mounted on iron frames similar to the stands of adding machines and can be placed in any position desirable, or, the cabinet can be mounted on a typewriter table and be placed under cover when the operator leaves. In fact these stands or cabinets can be placed in any position desirable, which shows the flexibility of my system.

It will be noted that I can make pro-

vision of a common impulse generator for the entire exchange, and that I employ individual selector zones (or wheels) having teeth of different lengths, these teeth being so proportioned, and the wheels so run relatively to the main commutator, that they will always make and break a little before and a little after the commutator circuit is made and broken, respectively, which positively avoids sparking at the contact pens. This arrangement is diagrammatically shown in Fig. 5, wherein I have illustrated the main commutator, one set of number wheels, an electric motor for driving the shaft common to all of these, and a set of operator's buttons similar to those shown in Figs. 13 to 18. Fig. 9 shows the same elements with the exception of the electric motor, which is therein replaced by an electromagnet controlling a clutch which throws power on and off from a constantly driven shaft. This is the preferred arrangement.

Attention is called to the details of the clutch $x20$ — $x30$ of Fig. 9. $x20$ is a toothed member and $x30$ is a member having a single tooth. By this arrangement a definite angular relation will be obtained between the driving shaft of $x20$ and the driven shaft of $x30$, hence between the teeth of the commutator wheel Q^{10} and the teeth of the toothed impulse wheels Q', Q^2, Q^3 , etc., whereby wheels Q', Q^2 , etc., may always break circuit with their pens in an interval of open circuit at the commutator Q^{10} .

Figs. 5 and 9 show what I shall call a multiple number transmitter having a common impulse generator for the entire exchange and individual selector wheels. In Fig. 5 I have shown these individual wheels being driven by a motor which starts up when the operator depresses the starting button. Fig. 9 shows the individual wheels being operated by a magnetically controlled clutch which when operated by the operator pressing the starting button, connects them to a constantly rotating shaft. The wheels Q', Q^2, Q^3, Q^5 are provided with teeth of different length. The tooth on wheel Q' being the shortest, while that of Q^5 is the longest, the tooth of the wheel Q' in passing over a contact pen transmits one impulse through the medium of the common commutator Q^{10} . The tooth of the wheel Q^5 in passing over one of these pens transmits five impulses through the same medium. A complete machine will have ten of these wheels so that any digit from one to ten can be indicated by sending the appropriate number of impulses. In the drawing, in order to economize space I show only the first five wheels. In practice, these wheels are all one, the teeth being formed upon the surface of a drum which is driven by a suitable motor or shaft. The speed which I have found most suitable for this device and for the type

of switches I here illustrate is approximately twelve revolutions per minute. For a one hundred line exchange which I am illustrating the first four wheels will be provided with three pens and the remaining six provided with two pens each. These pens through which the impulses are transmitted are connected in their proper order to the buttons of the sets K' , K^2 and K^3 . Thus the pen q is connected through wire 74 to the individual spring of the first key in the set K' , the pen q' of the cam Q^2 is similarly connected through the wire 75 to the second key of the set, and so on for all the pens of the first set. The second set of pens q^2 are similarly connected in order to the individual keys of the set K^2 , and the third set of pens q^3 are similarly connected to the keys of the set K^3 . The layout in the drawings is intended for an exchange of one hundred lines or less, the two sets of keys K' and K^2 serving to control two sets of number wheels for line selection purposes while the third set of keys K^3 is intended in the present case for selective ringing on party lines.

The wheel Q containing the three teeth transmits what is commonly called the rotary impulses to affect the side switch mechanism in the connector switch. The impulses from this wheel instead of being controlled by battery through the medium of the commutator Q^{10} send grounded impulses operated directly by the teeth coming in contact with a single pen. The wheel Q^{25} has an insulated point upon which the contact spring q^6 normally rests. After this wheel is started by the operation of the motor or clutch the pen q^6 riding on the metal portion of the wheel maintains a closed circuit for the motor which will continue to run until the wheel Q^{25} has made one complete revolution and the pen q^6 again rests on the insulated portion. The controlling circuit may be traced as follows: battery B, Q^{25} , q^6 , wire 82 (passing from Fig. 5 to Fig. 6) to relay H and ground. The relay H is pulled up as soon as the starting key is pressed, this starting key K^{10} merely putting battery on to the relay in parallel with the wheel Q^{25} . The relay H closes the following circuit: battery B (Fig. 6) wire 29, armature h , wire h' , to relay H' and ground. Relay H' therefore remains energized as long as relay H holds up, and the motor circuit is maintained closed by the following path: (in Fig. 6) from the dynamo or motor supply battery, or the main feeder circuit thereof, by wire 47 to armature h^a , h' , wire 85, into Fig. 5 and to the motor, then returning by wire 86 into Fig. 6, and thence back to the dynamo or battery. The teeth on the wheel Q are so set that they come successively in contact with its pen immediately after the teeth of the impulse wheels have ceased sending their

respective impulses, so that a complete signal will consist of (1) a set of number digits; (2) a rotary impulse; (3) another set of number impulses; (4) another rotary impulse; (5) a third set of number impulses; and (6) a final rotary impulse.

The common springs 790 of the key set with the exception of the springs 790 of the button K^{10} are connected together to a common wire 79. This common wire carries the actuating impulses to the switches in proper sequence. To illustrate clearly the operation of this device, suppose it be desired to transmit over the wire 79 the number 43-3. The operator depresses the fourth key in the first set and the third key in the second set, and finally the third key in the third set. Thus the spring q' of the wheel Q^4 becomes connected to the wire 79; the spring q^2 of the wheel Q^3 becomes connected through its wire to the wire 79, and the spring q^3 of the wheel Q^3 becomes connected through its wire and number key to the common wire 79. Now as the drum or the wheels rotate what happens is this: first, four impulses from the wheel Q^4 , then a single impulse from the wheel Q^3 , then three impulses from the wheel Q^2 ; then one impulse from the wheel Q ; then three impulses from the wheel Q^3 , and finally a single impulse from the wheel Q , so completing the signal. Any one familiar with the Strowger system of switches will at once perceive that the wires 79 and 84 (these being respectively the vertical and the rotary impulse wires) can be connected directly to or so as to repeat into the vertical and the rotary side of a switch trunk, respectively, and the impulses will then serve to operate the switches perfectly. I may here state that the sole function of the wheel Q^{25} with its wiper q^6 is to send in one complete set of impulses and then stop. Obviously, if the operator sets up the signal keys and the impulses were permitted to go directly into the switch circuits without any starting point, great confusion would result. For this reason I have the various signal wheels always come to rest at a normal starting point which is controlled directly by the wheel Q^{25} and the pen q^6 . The circuits of Fig. 5 thus described are particularly adapted to coöperate with the trunk circuit shown in Fig. 6.

Having thus described the mechanical parts, attention is invited to Fig. 21, which shows the general plan or layout of the circuits. This figure contains no reference letters, but is inscribed with suitable legends instead. The subscribers' stations are shown connected to the central office by line wires which are multiplied into the primary selectors (which may be either relay sets as shown in Figs. 2 to 4 inclusive, or switches as shown in Fig. 19), and each

primary selector talking trunk passes to a terminal selector switch through which access may be gained to wanted subscribers. In order to gain access to more than one hundred lines, it is necessary to provide additional groups of switches, such as "second selectors," "connectors," etc., but as the use of such supplemental groups is perfectly well known in the art, I have merely indicated all of the selective switching apparatus in Fig. 21 by the outline of a square in each case. This selective switching apparatus contains multiple contacts of the subscribers' lines, which for convenience are shown as of the same group which are multiplied to the particular primary selectors also shown in the figure. To control the selective switches, operators' key sets are provided, each connected to a secondary selector set (which may be either of the relay type shown in Fig. 6 or of the switch type shown in Fig. 19), and multiple taps are taken off from the talking trunks and carried into these secondary selectors.

When one of the subscribers calls, current in his line causes the actuation of an idle primary selector whereby he becomes connected to an idle talking trunk and its terminal selective switch or switches. The trunk being thus put in commission, has produced within it circuit changes which cause an idle secondary selector to pick it up and connect it to the corresponding idle operator's key set. There may be several of these key sets for each operator, and in fact all three key sets shown in the figure may be located in front of a single operator if desired. The number of operators and the number of key sets provided is of course determined by the traffic conditions depending on the number of lines to be served, and the extent of their use. The operator receiving the number orally, sets up her keys and thereby permits a corresponding number of impulses to pass over the talking trunk to the selective switches, which are thereby actuated to connect the trunk with the wanted line. The secondary selector then becomes automatically disconnected, the operations of testing, ringing, and finally disconnecting the lines being mechanically performed and entirely independent of the operator.

Having thus described the mechanical parts a knowledge of which is essential to the comprehension of my circuits, I turn to the description of the latter, beginning with Fig. 1. Therein I have shown three subscribers' stations, A, A', A², each equipped with a telephone transmitter, a receiver, a switch-hook, a ringer, and condenser, all of usual or suitable type for use with common battery circuits. When the hook is up, that is, when it is relieved of the weight of the receiver, the circuit is through the transmit-

ter and receiver; and when the hook is down, the line-circuit is completed for alternating current only, through the ringer and condenser.

Since the circuits are the same for all the lines, I will refer to the line from station A² only. This consists of conductors 1 and 2, extending from the substation to the central office. At the substation the talking circuit is completed through the wires 3-4 when the hook is up, and the ringing circuit through the wires 5-6 when the hook is down. These figures are useful for the purpose of tracing the circuits only.

Turning to Fig. 2, the line-wires 1 and 2 appear at the left hand side of the figure terminating in contacts of the cut-off relay, M', which is normally deenergized, so that in each case the line-wire 2 is grounded at 7 and the line-wire 1 extended through wire 8 to the line-relay M, and so to main battery B and ground. The armature, m, of each line-relay M is grounded at 9, and when attracted is adapted to close upon terminal contacts of wires leading to the tens and units relays of the primary selector sets. I preferably divide all the incoming lines in an exchange into groups of say one hundred each, and to each group I apportion a fixed number of trunks leading to connective apparatus. In a small or comparatively inactive exchange the percentage of these trunks may be as low as five, and in busy exchanges it may be raised to ten or even fifteen. I assume, however, that ten per cent. of connective apparatus will be sufficient to care for the present system; hence I provide ten trunks for each one hundred lines, and a complete set of tens and units relays in a primary selector group for each trunk. The circuits herein illustrated show six lines, which for convenience I will call Nos. 500, 501 and 502 (Fig. 2) and 510, 511 and 512 (Fig. 3). The subscribers' circuits of Fig. 1 will fit any of these, and in order to fully comprehend the connections of these lines and the arrangement of the tens and units relays, it is necessary to consider Figs. 2, 3 and 4 together. In Figs. 2 and 3 the subscribers' extension lines are shown coming into their initial terminals on the tens relays, which are of the type shown in Figs. 11 and 12. Each of these relays carries the terminals of ten lines, and for each trunk there are ten of these relays, so that for 100 lines, provided with ten trunks, there will be 100 ten point relays, containing 1,000 line-terminals; from which it appears that each line can be multiplied ten times, which it should be in order to obtain access on occasion to every one of the ten trunks. The contacts on the ten point relays are arranged in duplicate pairs. That is, the incoming lines terminate each on one pair of springs, opposite which another pair of springs appears to which the line is con-

nected when the relay is energized, and from which a local circuit passes to the front contact springs of a particular units relay or single point relay. For each group of ten tens relays there are ten units relays, or twenty relays in all for each trunk. A group of this kind constituting one primary selector trunk terminal for thirty lines, is shown in Fig. 10, apart from the other figures, so as to free the lines from their multiple connections. In order to make clear the connection of a line coming into the exchange, I will first refer to this figure and then trace the circuits through the others.

In Fig. 10, N , N' , N^2 , are three relays of the type shown in Figs. 11 and 12, having ten pairs of contacts each for the line-circuits. These relays correspond to the relays shown in Figs. 2 and 3, correspondingly lettered. At the top of the figure, I have shown the terminal ends of lines 500 to 529, inclusive, each connected to a pair of contacts, n^3 , n^5 , such as shown in the mechanical Figs. 11 and 12. For lines 500 to 509 these terminals are in the relay N . For lines 510 to 519 they are in the relay N' . For lines 520 to 529 they are in the relay N^2 . Thus each relay contains line-terminals, n^3 , n^5 , for ten lines. When any one of the lines approximated to a particular relay is calling, the electromagnet, n' , of that relay becomes energized. This will be explained in connection with the circuits of Figs. 1 and 2 farther on. For example, if any line from 500 to 509 originates a call, the magnet, n' , of the relay, N , will become energized, and simultaneously connect all of the lines from 500 to 509 onto the extensions 10' to 19' inclusive. If, however, the calling line is in the group from 510 to 519, the magnet, n' , of the relay, N' , will become energized, connecting all that group onto the extensions 10' to 19', inclusive. Similarly, if the calling line be in the third group, from 520 to 529, the magnet, n' , of the relay N^2 will be energized, connecting that entire group onto the extensions 10' to 19', inclusive. Thus extensions 10' to 19' are seen to be common to all of the tens relays, and in fact each extension pair is multiplied to corresponding contacts in all of the tens relays. No. 10' extension goes to the first pair of contacts, n^4 , n^6 , in each of the relays N , N' , N^2 . Extension No. 11' is multiplied to the second pair of contacts, n^4 , n^6 , in each of the relays, and so on with all the extensions up to No. 19'.

At the lower edge of Fig. 10, I have shown ten units relays, marked P to P^2 , inclusive. These are the same as the relays in Fig. 4, similarly marked. Each is a simple standard relay, of the type in common use, and preferably of the same general type as that shown in Figs. 11 and 12 hereof, viz., that type in which the electromagnet is mounted

horizontally on a frame or rack, carrying the contact springs upon it, and the whole is inclosed within a dust-proof shell. Each relay has an armature, p^2 , adapted to be actuated by an electromagnet, p' , to close together the contacts, p^8 , p^4 , and p^5 , p^6 . In the present instance, that is in the trunk group of each primary selector, all of the contacts, p^6 , of the entire set of relays, P to P^2 , are connected together, forming a set of double parallel branches marked 20 to 29, inclusive, which are really so many bridges across the trunk circuit, 30-31.

The equipment shown in Fig. 10 is sufficient for 30 lines, and by its use any one of the lines, 500 to 529, may connect itself to the trunk 30-31, by merely closing its line-circuit, and energizing the appropriate tens and units relays. The energizing circuits are not shown in Fig. 10, but will be described in connection with Figs. 2, 3 and 4. They comprise parallel branches closed by the line-relay of each line when calling, one branch going to the appropriate tens relays, and the other branch going to the appropriate units relay, which thus become energized simultaneously and act in conjunction to connect that particular line and no other to the trunk. For example, suppose line No. 512 is calling, the subscriber having taken his receiver from the hook, so as to close his line-circuit as shown in Fig. 1, and energize his line-relay, M , shown in Fig. 3. This line-relay closes two branches, one leading to the tens relay, N' , in Fig. 10, and the other leading to the units relay, P^2 , which is the third in the set of ten. The actuation of the tens relay, N' , connects all of the lines 510 to 519 onto the extensions 10 to 19, inclusive; but it will be observed that these extensions are open everywhere else, hence no effect is produced by this action alone. The third units relay, P^2 , however, connects the third extension 12 to the trunk 30-31, through the branch 22, and by following the circuits in Fig. 10 it will be found that this connects the line 512 onto the trunk direct, whereupon other trunk relays become energized and further proceedings may be had. Only one line is thus connected to the trunk at a time, assuming of course that only one tens relay and one units relay of the same set be energized simultaneously. It is true that the tens relay connects all of its lines onto the extensions; but all of these extensions are open except the particular one which is closed onto the trunk by the particular units relay energized. It is also true that the extension thus connected to the trunk is multiplied to the corresponding pair of contacts in every one of the tens relays, but this produces no effect, because all but one of the tens relays remain deenergized.

Before passing from Fig. 10 it is necessary to call attention to the fact that only

three tens relays are there shown, accommodating thirty lines. This limitation is due to the necessary limitation of a Patent Office drawing, and it is to be understood that the same principles apply to any desired group up to 100 or more. It is most convenient in a scheme like this to make use of the decimal system, using ten relays per trunk, ten lines per relay, and ten trunk multiples per line. For 100 lines there would be ten of the tens relays, N , N' , N^2 , etc., but still only ten of the units relays, and each of the extensions 10' to 19', inclusive, instead of being multiplied three times, would be multiplied ten times, into all the tens relays.

Turning to Figs. 2, 3 and 4 we have here the same relays described in connection with Fig. 10, but somewhat differently arranged. 20 Only two tens relays and three units relays of each set or of each trunk are shown: I have assumed the numbers 500, 501 and 502 for the lines entering Fig. 2, and 510, 511 and 512 for the lines entering Fig. 3. The 25 first three lines being within the same tens digits with each other go onto the same tens relays in each set. For the sake of convenience I have given the designating numerals of the relays coefficients. Thus in Fig. 2 30 all three of the lines come into the relay N , which is adapted to put them onto the extensions, 10', 11', 12', etc., leading to the units relays, P , P' , P^2 , etc., in Fig. 4. (I should here remark that the tens relays in Figs. 2 35 and 3 are not shown with their full complements of springs, for the sake of simplicity. Each of them is supposed to have ten pairs of contacts, in accordance with the showing of Figs. 11 and 12.) Each of the lines 500, 40 501 and 502 not only terminates in contacts of the relay, N , but is multiplied to similar contacts in the relays $1N$, $2N$, etc., pertaining to additional trunks serving the same lines. There would be one of these added 45 for each trunk, that is appropriated to the group of lines. In the present case I only illustrate three trunks, so that each line would be multiplied only three times.

In Fig. 3, the lines 510, 511 and 512 are 50 connected to the tens relays, N' , $1N'$ and $2N'$, in the same manner as the lines in Fig. 2, each line being multiplied three times so that each may have access to any one of the three trunks. It will be understood of 55 course that the relays, N , N' , of Figs. 2 and 3, and P , P' , P^2 , of Fig. 4, constitute one set, appropriated to the trunk 30—31, and have precisely the same relation among themselves and the same connections as the 60 set shown in Fig. 10. Similarly the relays $1N$, $1N'$, $1P$, $1P'$, and $1P^2$ all belong to one set, appropriated to the trunk-line 130—131. Similarly again, the relays $2N$, $2N'$, $2P$, $2P'$, and $2P^2$, belong to one set, appropriated 65 to the trunk-line 230—231. The extensions

from the tens relays to the units are marked 10', 11', 12' for the first set, 110, 111 and 112 for the second set, and 210, 211 and 212 for the third set. As these of course bear a logical relation throughout, and follow the 70 same arrangement as that in Fig. 10, it is through no difficulty will be experienced in comprehending the meaning of Figs. 2, 3 and 4. If Fig. 10 is understood, the description of the other figures may be put 75 into one sentence. They show several group like Fig. 10, with the line-wires multiplied to each group instead of terminating as in Fig. 10 in single pairs of contacts.

The actual connections controlled by the relays N and P being thus understood, it is most important to explain the means by which I control these relays. Referring to Fig. 2, the line-wires 1 and 2 terminate as 80 I have stated, in the contacts of the cut-off relay M' , through which they are normally connected to the line-relay M and ground, respectively. When the subscriber at station A^2 takes the telephone from the hook, 85 he closes his line-circuit, the line-relay M is energized, and the two branch circuits 50 and 51 are immediately closed. The branch 50 passes in multiple to one winding of each of the three tens relays, N , $1N$ and $2N$, these 90 relays being double-wound for the purpose of making them self-locking when attracted. Any one of these relays might thus be energized by any one of the three lines shown, 95 but it is shown later herein that only one of them may be so energized at once, and that no two lines shall be able to energize the same relay at the same time.

Referring to Fig. 6 the arrangement of this trunk 30—31 is as follows: To the incoming end of the trunk wires 30 and 31 are connected the relays D and D' , respectively. The relay D is normally disconnected from ground through the relay D' . The relay D' becoming energized in series with the line cut-off relay through the talking contacts of the primary selector relays, attracts its armatures and connects ground to the relay D , thus furnishing a circuit for talking current to the calling subscriber. 105 The relay D' also controls the circuit of the relay D^x which becoming energized opens the circuits leading to the actuating windings of the various relays in the primary selector set, thereby preventing any relay of the primary selector of the trunk 30—31 from responding to any subsequently calling line so long as the relays D' and D^x remain energized. The particular primary relays which have already responded to the 110 calling line, however, remain energized because of the formation of separate locking circuits controlled through the wire 57. Let us assume that subscriber A^2 has called in Fig. 1, that his line relay M has pulled up, 115 120 125 130

and that the primary relays N and P^2 have pulled up, these two relays corresponding to the number of that line and adapted to connect it to the trunk 30-31. The relay N immediately forms a locking circuit for itself as follows: from battery B in Fig. 6 through 28, 17, 14, 57 (into Fig. 4), 61, secondary winding P^2 , locking contact and ground back to battery. The locking wire 14 in Fig. 6 is common to the locking windings of all the primary relays associated with the trunk 30-31. It is controlled first by the relay E which is normally deenergized, and second by the relay D , which pulls up and remains energized during conversation. The contacts e^2, e^3 are provided merely in order to insure the normal connection of battery to this wire before the relay D has responded to the call. The moment the trunk becomes connected through these relay contacts with the line, current flows from the battery in Fig. 6 through the sleeve relay of D' and through the trunk wire 31 to the line sleeve extension and the cut-off relay M' , which immediately snaps its armatures down so as to connect the line wires 1-2 onto the extensions whereupon the battery current through trunk wire 31 will also flow out to line and back through the trunk wire 30 to the tip relay D which will thereupon pull up. The method of energizing the relay E will presently appear and it is sufficient to say here that as soon as the tip relay D responds, it takes control of the connection and thereafter the subscriber A^2 holds the same subject to his own will. When he hangs up the relay D lets go and permits the primary relays to clear out and release the line by breaking the locking circuit aforesaid.

The relation existing between the several trunks of the same group whereby one idle trunk of that group always stands ready to respond to a calling line is illustrated in Fig. 22. Here the trunk 30-31 stands normally ready to respond to the first call in its group of lines, by reason of the closed contacts of its relay D^x , through which the battery wire 28 is normally connected to wires 54, and thence through the actuating windings of the primary relays of the trunk, to the line relay contacts whereby the operation of any line relay will cause the proper primary relays to pull up. The primary relays of other trunks, however, will not be energized as long as trunk 30-31 is idle, because their respective wires 54 are disconnected from battery through the contacts of relays $1D^x, 2D^x$, etc. When the relay D' pulls up in the first trunk, after a call has landed on that trunk, the contact d^x puts current on its own associated relay D^x and through wire 600 to the relay $1D^x$ of the next trunk. The relay $1D^x$ of that trunk when it comes into service cuts off battery from its own relay

$1D^x$ and puts it onto the corresponding relay $2D^x$ of the next trunk, and so on. If this arrangement is made use of the relays subsequent to the first one must have their contacts normally opened, since they are successively energized instead of deenergized to put the trunks into commission. I prefer the arrangement of Fig. 22 since this involves the merest duplication of what is shown in Fig. 6.

The function of the primary relays of my system is to connect an idle trunk with a calling line. The call upon the line at first energizes the line relay M and extends no farther into the system. In response to the call a trunk connects with the line. The call now extends into the central office system as far as the trunk, and as the call is not yet satisfied the trunk in this condition may be referred to as a calling trunk. In a calling trunk the relay D' is energized as the relay M is energized in a calling line.

I provide operators' equipments as shown in the lower portion of Fig. 6, which are connected with conductors constituting substantially secondary trunks. The secondary trunk or operator's equipment is adapted to respond to a call upon a main trunk in a manner analogous to the response of a main trunk to a call upon a subscriber's line. In this analogy relay D' of the main trunk corresponds to relay M of the line; relay F of the secondary trunk corresponds to the tens relay N or N' of the main trunk; relay F' corresponds to the units relay $P P'$ or P^2 of the main trunk; relay F^2 corresponds to relay D^x of the main trunk; relay T of the secondary trunk corresponds to relay D' of the main trunk in that it controls the energization of relay F^2 and in that it controls the signal lamp L which calls for the response of an operator just as relay D' calls for the response of a secondary trunk or as relay M calls for the response of a main trunk. A relation or condition of precedence among secondary trunks exists which parallels the condition just described above existing among main trunks. This arrangement in the secondary trunks is shown in Fig. 23. In this figure the lower trunk has closed contacts upon relay F^2 while the upper trunk has open contacts upon relay $4F^2$ whereby the potential of battery B is passed through the contacts of relay F^2 to the actuating windings of the relays $F F'$ of the operator's set of which the listening key Kx is a part, the path from battery B thence extending over wires 18 and 118 upward out of Fig. 23 and into Fig. 22, thence through back contacts on relay E to contacts at armature d^x of relay D' , to ground and back to battery.

The secondary tens relay F is that relay of the operator's set which contains multiple terminals of that group of ten trunks of which trunk 30-31 is one; the units relay

F' is that relay which contains a pair of terminals corresponding to the units digit of the trunk 30-31 in the group, counting from 0 to 9, or from 1 to 10. An additional operator's set, of which the listening key $4K^x$ is a part, has similar tens and units relays $4F$ and $4F'$. It is understood of course that each secondary trunk has its full equipment of a plurality of tens relays and a plurality of units relays for answering calls upon main trunks just as each main trunk has a plurality of relays of each class for answering calls upon lines. The main trunks are multiplied into contacts of relays F , $4F$, etc., as lines are multiplied into relays N , N' , etc.; the secondary trunks, viz. wires 39-40, are multiplied into all the first relays of each secondary set of relays just as the talking conductors 30-31 of any main trunk are multiplied into all the units relays of the primary selector set pertaining to that main trunk. By the actuation of a tens and a units relay of a secondary set, the secondary trunk 39-40 is connected to the main trunk 30-31. This results in energization of the relay T over the following path: battery B , of Fig. 6, wires 28-29, 42, armature h^9 , contact h^{10} , wires 41, 38, 36, 43, winding of relay T , contacts t^2 t' , wire 44, contact h^2 , armature h^3 , wire 40, contacts of relay F' , wire 35 (see Fig. 6), contacts of relay F , wire 32 and winding of relay S to ground. In response to this current relay T is energized and locks itself to earth by connection of armature t with contact of t^2 . By its armature t^3 it closes path for current from battery B over 28, 29, t^3 , t^4 , F^2 to earth, breaking contacts of F^2 whereby all actuating windings of the secondary set of relays are opened; also over path B , 28, 29, t^3 , t^4 , 602, $4t^3$ and winding of relay $4F^2$ to earth, energizing relay $4F^2$ which through its contacts passes potential of battery B to the actuating windings of all relays of the secondary set pertaining to the secondary trunk 639-640. Thus secondary trunk 39-40 may not respond to further calls until after having been released and secondary trunk 639-640 will respond to the next succeeding call.

It should be understood that the relation between the trunks involves mere duplication, and therefore I may duplicate the relays T and F^2 in the same relation in each secondary trunk, simply cutting battery from one to the other in a well known manner. This idea as applied to the main trunks and their primary selectors is illustrated in Fig. 22, so that further illustration would seem unnecessary. The particular arrangement of the armatures of the relays T , F^2 or D^x (Figs. 6, 22 and 23) is non-essential, so long as the desired function is performed, to cut off the primary and secondary relays of the trunks that are out of commission, so

that only one trunk at a time, either primary or secondary, will be active to receive calls.

The relay E of the main trunk is the starting relay and becomes energized only when the calling main trunk is responded to by the secondary trunk. One of its functions is to annul the calling condition of the calling trunk, which it does by opening wires 18 and 118 at its armature e' . These secondary sets of relays are only connected to the talking trunk for a short period; that is to say, until the operator has received the number wanted and set up the impulse keys, thus transmitting impulses to the switching mechanism attached to the outgoing end of the talking trunk. The relays S and S' respond to the impulses from the sending machine and repeat the impulses to the outgoing end of the trunk and at the same time open the incoming end of the trunk preventing the calling subscriber from receiving annoying clicks. The relay H is controlled by the starting button K^{x1} shown in Fig. 5. The operation of the relay H closes the circuit of the relay H' which in turn connects battery for suitable current to the motor, Fig. 5, thus causing the impulse wheels to rotate. When the relay T becomes energized it causes the lamp L to glow thus notifying the operator that a party is calling. She thereupon depresses the listening button, K^x , which connects her talking set, which is connected to the wires 49 and 50, to the wires 32 and 33 through the relays F and F' . The relay S is connected to ground while the relay S' is connected to battery and as soon as the operator bridges her telephone set across these wires these two relays become energized and connect her talking set across the trunk wires and at the same time supply her with battery for talking. These two relays in drawing up their armatures also perform a very useful function of placing battery simultaneously on both sides of the trunk wires leading to the switching mechanism. If any of these switches by chance were left in an operated position they would at once be restored to their normal position. The relay H while being first controlled by the starting button K^{x1} is held energized as it is connected to the pen q^6 and when this pen rests on the metal wheel Q^{25} the relay is held energized until one complete revolution has been made. After one complete revolution this relay drops back and momentarily opens the locking circuit of the relays F and F' , thus disconnecting the secondary equipment from the talking trunk and leaving it in condition for another incoming call. The locking circuit of the relays F and F' is controlled by the normally open contact h^5 of the relay H and the normally closed contact h^6 of the relay H' and it of course follows that if a

condition be brought about such that the relay H' is energized while the relay H is de-energized, then this locking circuit would be opened for an instant. The locking circuit 5 of the relay T is in multiple with that of the relays F and F' and it of course follows that it is affected in the same manner. When the relay H' becomes energized the guard lamp L' glows and will continue to glow until the 10 entire number has been sent, thus notifying the operator that the number is being transmitted. The circuits will be traced in detail when I describe the operation of my system. After the talking trunk is connect- 15 ed to a secondary selector set the relay S becoming energized on account of being placed in series with the relay T for a short time, attracts its armature and closes the circuit of the relay E , as follows: battery B , 28, 21, 20, s , s' , 20, E , 15, d^6 , d^5 , to ground and back to battery which thereupon locks itself by way of wire 17 and armature e^3 , and remains in that condition controlled by the relay D' . The energizing of the relay E disconnects wire 18 from its grounded connection 15 thus preventing the same trunk from picking up another or the same set of secondary relays after the impulses have been sent.

Referring to Fig. 7 the connector switch 25 includes the vertical relay V which responding to impulses over the vertical side of the trunk operates the vertical magnet V^2 which in turn causes the spindle Z carrying the wipers z' and z to step up vertically. The relay V' connected to the rotary side of the trunk responds to rotary impulses and operates the private relay U which in turn causes the mechanically operated side 30 switches to move one point, disconnecting the vertical magnet V^2 and in its place connecting the rotary magnet V^3 , and at the same time through the side switch w^8 connects the tip side of the trunk to a contact in the private relay which, when closed, 35 connects the test relay J . The relay V responding to a second set of impulses over the vertical side of the trunk operates the rotary magnet V^3 causing the spindle Z to rotate and bring the wipers to rest on contacts leading to desired lines. The next rotary impulse coming in operates the private 40 relay U in the same manner as before, causing the side switches to make still another movement. This last movement of the side 45 switches disconnects the rotary magnet and in its place connects the relay R' which, when operated closes the circuit of the locking relay X' , as follows: battery B , wire 50 309, contact r' , armature r , wire 320, relay X' , r^8 , r^2 , to ground and back to battery. Relay X' then completes the circuit of the 55 ringing relay Y . As long as the relay R' is deenergized its circuit is: B , 309, Y' , 319, Y , x^4 , x^5 , r^{10} , r^2 , and ground back to battery.

While the relay R' remains energized for other purposes, however, the ringing relay is disabled by the opening of the contacts r^2 , r^{10} . This occurs during the ringing selection which is now to be described. The relay R' is now in position to be controlled by the third set of impulses coming in over the vertical side of the trunk. This relay controls a set of relays W and these relays in turn control generator current of different frequencies or polarities. All of these relays are self-locking and have a common wire controlling their locking circuits. This common wire, 150, leads to a normally open contact in the relay X' . This relay becoming energized at the first impulse of the third set places battery on this wire. The relay R' is also energized at this juncture and after the first impulse its armature drops back and closes the circuit of the relay W^4 through the normally closed contacts of the relay W^5 as follows: B , 309, x^3 , x^2 , r^6 , r^7 , 315, w' , w^2 , W^4 and ground back to battery. It will be noted that relay X' remains locked as long as the switch is "off normal" and the called subscriber has not answered, on the following path: B , 309, r' , r , 320, X' , x , 313, z^2 , z^3 and ground back to battery. When the subscriber answers, relay R responds, opens the contacts r , r' , 95 and then the relay X' is released but not before. The next impulse operating the relay R' closes the circuit of the relay W^5 through the contacts of the relay W^4 and the normally closed back contact of the relay W^6 , and after the second impulse the front contact of the relay W^6 is closed through the contacts of the relay w^5 . At the third impulse the circuit of the relay W^7 is closed through the contacts of the relays W^4 and W^6 and the normally closed contacts of the relay W^8 ; at the end of the third impulse the circuit of the relay W^8 is closed through the contacts of the relays W^5 and W^7 and the normally closed contacts of the relay W^9 . At the fourth impulse the circuit of the relay W^9 is closed through the contacts of the relays W^4 , W^6 and W^8 . It will be seen from the foregoing description 100 that I have a set of step by step relays controlled by the relay R' , the first relay of the set becoming energized when the relay R' becomes deenergized, the second relay becomes energized when the relay R' becomes energized the second time, and the third relay becoming energized when the relay R' becomes energized the third time, and so on. This system of relays can be carried on indefinitely. The relay W^5 becoming energized disconnects generator G' and in place 105 connects the generator G^2 to a contact in the ringing relay Y , and the relay W^7 becoming energized disconnects the generator G^2 and in its place connects the generator G^3 and the relay W^9 becoming energized dis- 110 115 120 125 130

connects the generator G^3 , and in its place connects generator G^4 .

Battery current is supplied to the called subscriber through the relay R and retardation coil I which are normally connected to the calling end of the trunk. The locking circuit of the relay X' is controlled jointly by the normally closed contacts of the relay R and the normally open contacts z^2 and z^3 controlled by the spindle Z . If the called subscriber answers, the relay R becomes energized, disconnecting the relay X' which in turn cuts off the ringing relay Y . If the called subscriber does not answer, the relay X' is disconnected when the calling subscriber hangs up his telephone disconnecting the switch Z which upon the return to its normal position opens the contact springs z^2 and z^3 . These contact springs are shown in Fig. 7 as arranged beneath and in the line of travel of the spindle of the switch, which is supposed to drop down and open the spring when restored or in inactive position. The calling subscriber at the end of the conversation automatically places battery on both sides of the trunk circuit operating the relays V and V' simultaneously, the action of which closes the circuit of the test relay J which in turn closes the circuit of the release magnet J' . Battery is placed on both sides of the trunk circuit by the combination of relays in the talking trunk circuit as follows: During conversation the relays D, D' and E remain energized. When the subscriber hangs up his telephone the relay D' is the first to fall back or become deenergized which places battery through its normally closed contacts to the contacts in the relay E and from there to the trunk circuit. The next relay to drop back or to become deenergized is the relay D' which is kept energized longer than the relay D on account of being in series with the line cut off relay through the primary selector sets. After the relay D' becomes deenergized the relay E is disconnected and thus battery is removed from both sides of the trunk.

Referring to Fig. 8, which is a modification of Fig. 6, the talking trunk is practically the same as shown in Fig. 6 consisting of the tip and sleeve relays D and D' , the starting relay E and repeating relays S and S' . In this case the tip relay D is normally connected to ground, and the starting relay E instead of being controlled by the action of the relay S is controlled directly by the relay T which is in series with it when the talking trunk is connected to the secondary set. This relay E is provided with a make before break contact and when operated locks itself and is disconnected from the wire 32, leaving it clear for sending impulses to the relay S . In the secondary set I have only provided a single signal lamp L having omitted the guard lamp L' shown in Fig. 6. The

locking contact of the relay T is provided with a resistance coil I^{10} . This coil prevents a short circuit when the two relays T and E are placed in series as the locking contact of the relay E is connected directly to battery through the contact of the relay D' and if the locking contact of the relay T were connected directly to ground there would be nothing to prevent a short circuit. In this modification I also omit the relay H' shown in Fig. 6, but in Fig. 9, which is a modification of Fig. 5, I have added the magnet X^{10} .

Referring to Fig. 9, in place of the motor I have substituted a clutch which is controlled by the magnet X^{10} . This magnet is controlled by the starting button in a manner similar to that in which the motor is controlled. The wheel Q^{25} instead of having an insulating point and one wiper or pen is provided with an insulating ridge upon which the contact spring $q20$ normally rests and at the same time is in connection with the spring $q10$. The contact spring $q30$ immediately under the spring $q20$ is normally open. The clutch is operated and controlled in the following manner: The operator upon getting the number desired pushes the starting button K'' which energizes the magnet X^{10} and also the relay H , Fig. 8. The relay H becoming energized extinguishes the lamp L . The operation of the magnet X^{10} attracts the arm or lever $\alpha50$ which engaging the movable clutch $\alpha30$ brings it into engagement with the constantly rotating clutch $\alpha20$. This action causes the various signal wheels to rotate in the same manner and at the same speed as the similar wheels in Fig. 5 are operated by the motor. As soon as the wheel Q^{25} starts to rotate the contacts $q20$ and $q30$ are closed. The contact $q30$ is connected to the winding of the magnet X^{10} and also to the relay H , Fig. 8. The contact $q20$ is connected directly to battery B , while the spring $q10$ is connected to the winding of the relay T , Fig. 8. It of course follows that both the relay H and the magnet X^{10} will remain energized while the wheel Q^{25} is rotating and until the insulated ridge again engages the contact spring $q20$. The relay T is held energized after the contacts $q10$ and $q20$ are broken by the relay H , as the winding of the relay T is connected to a contact in this relay. After one complete rotation or when the ridge engages the spring $q20$ the magnet X^{10} as well as that of the relay H becomes deenergized the impulse wheels ceasing to rotate and the secondary set disconnected from the talking trunk. The number wheels and impulse keys are the same as in Fig. 5, and need not be described. In this specification a description of the operation will include Figs. 5 and 6 and an understanding of the operation of the circuits shown in those figures will enable

anyone to understand the circuits of the modifications shown in Figs. 8 and 9.

I will now describe the complete operation of the foregoing system, as a preliminary to stating in explicit terms the method which I claim, as contradistinguished from the system or the apparatus. Assuming that subscriber A², in Fig. 1, wishes to call, when he takes down his receiver his line circuit, 5 1—2, is closed, the relay M pulls up (and assuming that all connective apparatus is idle) the relays N and P², in Figs. 2 and 4, pull up, their return wires, 54 and 60, being normally closed through the contact of the 10 relay D^x, Fig. 6. The extension wires from the cut-off relay M' are thus prolonged by way of contacts 502 and wires 12 to the trunk 30—31 in Fig. 4, and so on to the same wires in Fig. 6. Current immediately 15 flows from main battery B in Fig. 6 through the sleeve relay D' and back through the sleeve side of the trunk to the cut-off relay M' to ground. The cut-off relay thereupon immediately pulls up putting the subscriber's line on to the extension and so on to the trunk whereupon the tip relay D of the 20 trunk pulls up. This closes battery to the wire 14 and to the locking wire 57 the wire 14 being previously connected to battery through the back contact e² of the relay E. The relays N and P² remain locked 25 therefore subject to the control of the relay D which is controlled directly by the calling subscriber. Drawings accompanying this specification only show one talking trunk, but it is of course understood that the full percentage is to be provided and that the secondary set shown in Fig. 6 can be connected to any one of the talking trunks. 30 When the relay D' pulls up it puts battery on the relay D^x which pulls up and cuts off all the return wires 54, of the selector relays N, P, etc., of its set. The trunk is thus disabled for any other call. At the same time 35 current passes through the wire 600 to the armature of a relay (1D' of Fig. 22) in the next trunk corresponding to the relay D' through a back contact thereof and so on to the relay 1D^x corresponding to the relay D^x which immediately pulls up and places battery on the actuating windings of the 40 relays 1N, 1P, etc., of its set. The next call coming in would be connected to the second trunk, and so on. The energizing of the 45 relay D' in addition to connecting ground to the winding of the relay D also places ground on the starting wires 18 and 118 of the secondary operator's set through the 50 normally closed contacts e and e' of the relay E. As the secondary set is idle the tens 55 relay F as well as the units relay F' will become energized. The energizing of these two relays connects the wires 32 and 33 leading to the relays S and S' respectively, to 60 the wires 40 and 39 of the secondary set.

The first thing that happens is the relay T is connected in series with the relay S by the following path: battery B, 29, 42, h⁹, h¹⁰, 41, 38, 36, 43, T, t², t¹, 44, h², h³, 40, 32, S, to ground. The relay T becoming energized 70 locks itself through the contacts t and t², opening the contacts t¹ and t², thus removing itself from the wire 40. The relay S being momentarily energized attracts its armature and closes the circuit of the relay E by the following path: battery B, 28, 21, s, s', 20, E, 15, d⁶, d⁵, to ground. The relay E thereupon locks itself through the contacts e⁴ and e⁵, as the contact e⁴ is connected to the winding and the contact e⁵ is connected to battery. The energizing of 75 this relay disconnects the starting wires 18 and 118 leaving them free from further interruptions by this trunk, and also takes battery off the locking wire 14, but as the relay D has become energized, another path to battery has been established thereby through the contacts d³, d⁴, so the potential of the wire remains constant. The opening of the starting circuit removes ground from the 80 actuating windings of the relays F and F' and they are now held energized through their locking windings by the following path: battery B, 29, 42, h⁹, h¹⁰, 41, 38, F, F' to ground, the relay F being held up in 85 parallel by the extension wire 36. The energizing of the relay T closes the circuit of the lamp L causing it to glow. The operator receiving the signal depresses the listening button K^x connecting her talking set across 90 the wires 32 and 33 through the contacts of the relays F and F'. This talking set being bridged across the wires 32 and 33 closes the circuits of the relays S and S', thus connecting the talking set to the trunk wires 95 through the contacts s², s³ and s⁷, s⁸, respectively. Through these two relays battery current is supplied to the operator's set, and at the same time they connect the set across 100 the trunk wires enabling her to converse with the calling subscriber. The action of these relays at this time places battery on both trunk wires 30x and 31x through the contacts s⁴, s⁵ and s⁹, s¹⁰, respectively. Battery current going over both sides of the 105 trunk at the same time, restores to normal the switching mechanism of Fig. 7 in case it had been left in an unrestored position through some fault of the relays when the trunk was last used. The operator now being connected to the calling subscriber and asking for the number depresses the buttons 110 of her key set corresponding to the number desired.

For illustration, suppose the number asked for was 43—3, the first two digits representing the telephone line number and the last digit representing the signaling number as I wish to illustrate the manner of selective party-line ringing. The operator depresses 115

the fourth key in the set K' , the third key in the set K^2 , and the third key in the set K^3 . Having thus set up the number the operator closes the starting key $K_{a'}$ thereupon closing the circuit of the relay H , Fig. 6, by the following path: battery B, 210, 73, 790, 82, H to ground. The energizing of this relay closes the circuit of the relay H' by the following path: battery B, 29, 42, h , h' , H' to ground. The energizing of the relay H' opens the locking circuit of the relays F and F' but the circuit is maintained through the contacts h^4 and h^5 of the relay H. The action of the relay H' closes the circuit of the lamp L' causing it to glow. It also closes the circuit of the motor Fig. 5 through the contacts h^6 and h^7 . Referring to Fig. 5 the starting of the motor X causes the impulse wheels to rotate. At the first movement of the wheels, the pen q^0 rides on the metal portion of the wheel Q^{25} , thus maintaining the circuit of the motor X, after the starting button is released. The common wire 79 receives the vertical impulses, that is to say, impulses from the wheels Q' , Q^2 , Q^3 , Q^4 , etc., from this wire the impulses are conveyed to the relay S through the contacts of the relays F and F'. The rotary impulses or the impulses from the wheel Q are conveyed to the relay S' through the same relays. The first set of impulses to be received by the relay S are those transmitted from the pen q' of the wheel Q^4 . These impulses pass through the contacts of the fourth button of the set K' , the next impulse is a rotary impulse sent to the relay S' by the wheel Q. The second set of vertical impulses are sent to the relay S by the pen q^2 of the wheel Q^3 through the contacts of the third button of the set K^2 , then follows another rotary impulse from the wheel Q. The third set of impulses are sent from the pen q^3 of the wheel Q^3 through the contact of the third button of the set K^3 , then follows the third rotary impulse. After the last set of impulses or after one complete revolution, the pen q^0 of the wheel Q^{25} rests on the insulated portion and the relay H becomes deenergized. The deenergizing of this relay opens the locking circuits of the relays F, F' and T, thereby disconnecting the secondary set from the talking trunk. The deenergizing of the relay H releases the relay H' and extinguishes both lamps L and L' . It, of course, follows, that as the operator's talking set is connected to the secondary set and the secondary set is disconnected from the talking trunk the operator is prevented listening in on the trunk during conversation. The secondary set is only connected to the talking trunk while the number is being taken, and while the impulses are being sent.

Referring to Fig. 7 I will show how these impulses from the secondary set which operate the relays S and S' in Fig. 6 control the

switching mechanism in this figure. I have already shown how the calling subscriber is automatically connected to a secondary set through a talking trunk, the secondary set simply containing the operator's set and impulse transmitter. I have also shown how these impulses from the various wheels affect the relays S and S'. The first set of impulses which, in this case number four causes the relay S to attract its armature four times and send that number of impulses over the wire $30a$ through the contacts s^4 and s^5 . These impulses coming in over what is known as the vertical side of the trunk operate the vertical relay V which in turn closes the circuit of the vertical magnet V^2 , by the following path: ground v^3 , v^2 , w , w' , 306, switch arm $w50$, 321, V^2 , 309, to battery B. The operation of this magnet causes the spindle Z carrying the wipers z and z' to step up vertically opposite a row of contacts corresponding to the number of impulses sent from the secondary set. After this first set of impulses a rotary impulse is placed on the wire 31^x or the rotary side of the trunk by the action of the relay S'. This impulse operates the relay V', which in turn closes the circuit of the private relay U which causes the side switch to move one step, placing the various arms, $w50$, $w60$, $w70$ and $w80$ on the second contacts. The movement of the arm $w50$ disconnects the vertical magnet V^2 and in its place connects the rotary magnet V^3 ; while the operation of the arm $w80$ connects or places the test relay J in position to test the tip side of the line.

The second set of impulses numbering three, operates the relay V which in turn closes the circuit of the rotary magnet V^3 causing the spindle Z to rotate and bring the wipers to rest on contacts leading to the desired line. The second rotary impulse now coming in operates the relay V' which closes the circuit of the private relay U causing the side switch to take another step bringing the switch arms to rest on the third contacts. During this second rotary impulse while the relay U is energized the test relay J is connected directly to the tip side of the line and if the line were busy the relay J would become energized and closing the circuit of the release magnet J' restores the switch to its normal position. We will take it for granted that the called line is idle, so therefore the switch arms rest on their respective contacts. The switch arm $w50$ disconnects the rotary magnet V^3 and in its place connects the relay R'. The switch arms $w60$ and $w70$ close their respective trunk circuits while the switch arm $w80$ disconnects the test relay from the tip side of the line or trunk. The calling subscriber is now connected to line number 43. The third set of impulses now coming in operate the relay V which in turn closes the circuit

of the relay R'. The first one of these impulses affecting this relay causes it to close the circuit of the relay X' by the following path: ground r₂, r₃, X', 320, r', r, 309, to battery B. This relay now locks itself through the contacts *x* and *x'*, the contact *x* being connected to ground through the springs z₂ and z₃ which are controlled by the switch spindle. The winding of the relay X' is connected to battery through the normally closed contacts *r*, *r'* of the relay R. Battery is now placed on the locking contacts of the ringing relay set W through the common wire 150 and the contacts *x²* and *x³* of the relay X'. The number of impulses in this last set are three which correspond to the ringing number of the desired party. The first impulse affecting the relay R' does not affect any other relays in the ringing set W, but immediately after the first impulse when the relay R' drops back the circuit of the relay W⁴ is closed by the following path: battery B, 309, 312, *x³*, *x²*, r₆, r₇, 315, *w'*, *w₂*, W⁴, to ground. The second impulse coming in operating the relay R' closes the circuit of the relay W⁵ by the following path: battery B, 309, 312, *x³*, *x²*, r₆, r₅, 314, *w₆*, *w₅*, *w₁₃*, *w₁₄*, W⁵, to ground. The operation of the relay W⁵ disconnects the first generator G¹ and connects the generator G² in its place to the normally open contact in the ringing relay Y. Immediately after the second impulse the relay R' dropping back closes the circuit of the relay W⁶ through the path already described to wire 315 and from there through *w'*, *w*, *w₈*, *w₉*, W⁶ to ground. The third impulse coming in closes the circuit of the relay W⁷ through the path already described to wire 314 and from there through *w₆*, *w₅*, *w₁₃*, *w₁₂*, *w₂₁*, *w₂₂*, W⁷, to ground. The operation of the relay W⁷ disconnects generator G² and in its place connects the generator G³ which is of proper frequency or polarity to ring the bell at the desired station. Immediately after the third impulse the circuit of the relay W⁸ is closed in a manner similar to that already described in connection with the other relays. The proper generator current is now placed on the contacts in the ringing relay Y. One terminal of the relay Y is connected directly to an interrupting machine Y' and the interrupting machine itself is connected directly to battery. The other terminal of the relay is connected to ground through the normally closed contacts r₁₀ and r₂ of the relay R' in series with the contacts *x⁴* and *x⁵* of the relay X'. While the ringing impulses are being sent and the proper relay in the ringing set W is being selected the relay Y is not affected on account of the rapid making and breaking of the contacts r₁₀ and r₂. After the impulses have been sent and the relay R' is in its normal position the circuit of the relay Y is

closed and opened through the interrupting machine Y'. When its circuit is closed the relay Y opens the answering end of the trunk and places generator current on the calling end of the trunk. This current is placed on the line intermittently and during one of these intermissions when the relay Y is deenergized and the called subscriber removes his telephone the relay R becomes energized and opening the contacts *r* and *r'* releases the relay X' which in turn opens the circuit of the ringing relay Y, thus preventing any further generator current being placed on the line. The retardation, or resistance coil I' is provided to hold up the cut-off relay of the line while generator current is being sent over the line. All of the generators have one terminal connected to battery and this coil having one of its terminals connected to battery insures a metallic ringing circuit.

From the foregoing description it will be seen that the two subscribers are provided with a clear talking circuit, battery current being supplied to the called subscriber from the connector switch and battery supplied to the calling subscriber from the trunk. In this present arrangement there are two sets of condensers in this talking circuit and also an additional bridge caused by the relays V and V' which are not needed at this juncture. The relay X' which is released when the called subscriber answers also unlocks the relays in the ringing set W thus preventing a waste of current.

At the end of the conversation the calling subscriber hanging up his telephone deenergizes the relay D and this relay dropping back opens the locking wire 14, releasing the relays N and P² which upon falling back open the trunk circuit disconnecting the relay D' and the line cut-off relay M'. The relay D being the first to fall back places battery on both sides of the trunk leading to the switching mechanism through the contacts e₅, e₆ and e₇, e₈. The relay D' is the next relay to drop back thereby releasing the relay E, removing the battery from both sides of the trunk. From this combination it will be seen that a momentary impulse has been placed simultaneously on both trunk wires. Referring to Fig. 7 this momentary impulse operates the relays V and V' closing the circuit of the relay J by the following path: ground, v, v', J, battery B. This latter relay operating closes the contacts *j* and *j'* energizing the release magnet J' thereby restoring the switch to its normal position.

It will not be necessary to describe the full operation of the modifications shown in Figs. 8 and 9 as these can simply be substituted in place of Figs. 5 and 6 and the results will be the same. I have preferred in giving a description of the full operation of

my system to use Figs. 5 and 6 as I have actually had the circuits as shown wired up and in full operation. The only practical difference between the figures used and the modifications themselves is that in place of a motor driving the impulse wheels I have shown the wheels being driven by constantly rotating shaft when the magnetically controlled friction clutch is operated.

10 From the foregoing description the following points will be observed: First, the calling subscriber is automatically connected to an idle talking trunk by means of a primary relay set. Second, from the talking trunk 15 he is automatically connected to an idle operator's set by means of a secondary relay set. Thirdly, the operator simply depresses a button to inquire the number. Fourth, after getting the number she simply sets it up 20 by depressing the proper buttons, after which the called party is automatically connected to the talking trunk. Fifth, after the number has been transmitted the secondary set as well as the operator is disconnected 25 from the talking trunk thus insuring positive secrecy. Sixth, the ringing is done automatically from the connector switch. Seventh, party line ringing is provided for so that any desired method of selective ringing 30 can be employed. Eighth, the disconnecting is done automatically when the subscribers have finished talking. Ninth, the operator has no means of knowing where or from whom a call originates, so there is no 35 chance for favoritism, and all parties in this case will receive the same amount of attention.

The operation of setting up the number by 40 pressing the proper button is sub-consciously controlled after sufficient practice has been had, as in any other case of purely manual dexterity such as typewriting. By actual trial the time consumed in receiving and setting up a number having five digits averages 45 about 2.9 seconds. A very little figuring will suffice to show that on a three second basis the operator could handle 20 calls per minute, or 1200 per hour. Taking one-half of this, I fix 600 calls per hour as a standard 50 maximum, and I furnish the operators with sufficient apparatus for this and no more.

It will be noticed by referring to the drawings that in the mechanical figures I have shown four rows of buttons per set and four 55 additional selective ringing buttons which would serve for a 10,000 line system, while in the circuit drawings I have only shown two rows of buttons and four additional selective ringing buttons. I have omitted 60 adding these extra buttons to the circuit drawings for sake of simplicity. To add the full equipment of buttons would mean inserting first and second selector switches and describing them in detail. The invention is

shown fully in connection with a hundred 65 line system, such as I have described, and additional apparatus would simply require repetition.

Fig. 19 shows a modification in the apparatus used for the primary and secondary selector functions in an exchange built according to the principles of my invention. In Fig. 19 the first selector set of relays is displaced by a mechanically-driven shaft moving wipers over fixed contacts, the wipers being trunk terminals and the fixed contacts line terminals. In this way the trunk constantly searches for a calling line and stops upon a calling line when such a line is found, the result being the same as with the 80 set of selector relays in Figs. 2, 3 and 4. The secondary set of relays is replaced by a similar power-driven call-seeking switch.

Figs. 7, 19 and 20 must be attached to form a diagram of the complete operating 85 system. The operation is as follows: Shaft 601, belonging to trunk 30-31, revolves continuously when the trunk is idle, and carries its wipers 603-604-605 over waiting contacts of the lines served by the group of 90 trunks of which the trunk 30-31 is one. When a subscriber, as at sub-station 606, calls, current flows over path B, 607, 608, contact and armature of 609, 610, 606, 611, armature and contact of 609, 612 and earth, energizing relay 608 and closing its contact, thus extending the battery potential to a 95 waiting contact 613 accessible to wiper 603. When wiper 603 in the course of its travel next makes connection with waiting contact 100 613, current flows over the path B, 607, armature and contact of 608, 613, 603, 616, armature and contact of D, 617, magnet 618 and earth, which energizes clutch magnet 618. Clutch magnet 618 operates its clutch 105 619 to disconnect the shaft 601 from the belt-driven pulley 620, thereby stopping the shaft 601 with the wipers 603-604-605 in connection with the waiting contacts 613- 110 614-615 respectively. Current now flows over path B, 621, D', 31, 605, 615, 609 and earth, energizing D' and 609; by the energization of relay 609, line conductors 610- 115 611 are disconnected from relay 608 and wire 612 respectively and are extended through contacts 614-615 and wipers 604- 605 to trunk conductors 30-31 respectively. Current now flows over path B, 621, D', 31, 605, 615, contact and armature of 609, 611, 606, 610, armature and contact of 609, 614, 604, 30, D and ground, energizing D. The 120 operation of armature 622 of relay D closes path for current through B, 621, 623, 622, 617, 618 and ground, maintaining the energization of clutch relay 618, the previous 125 path for energizing that magnet having been broken by deenergization of relay 608 following the energization of relay 609.

This is the complete cycle of operations for the connection of an idle trunk to a calling line.

Passing now to the connection of an idle operator's set, as K_{xi} , to the trunk 30-31 which now is a calling trunk, we have similar apparatus in the shaft 624 and clutch magnet 625. The energization of relay D' extends the ground upon its armature over

conductors 626, 627 to waiting contact, 628. When wiper 629 makes connection with contact 628, path is closed for current as follows: B, 630, 631, 625, 632, armature and contact of T, 634, 629, 628, 627, armature and contact of F, 626, contact and armature of D and ground. This energizes clutch magnet 625 and stops the motion of the wipers 629-635-636, holding them in connection with contacts 628-637 and 638 respectively. Current now flows over path B, 630, armature and contact of H', 639, 640, T, closed contact of T, 633, 636, 638, S and earth, energizing T which locks over its armature t and which by its armature t' furnishes ground for clutch magnet 625. By this energization of relay S also, current flows over path B, 621, 641, armature and contact of S, 692, F, contact and armature of D' and ground, energizing relay F which locks over the path B, 621, 642, F, armature and contact of D' and ground. This energization and locking of relay F breaks the connection between wires 626-627 and takes the calling condition off of waiting contact 628 so that other operators' trunks will not find the main trunk 30-31 calling, and therefore will not stop in connection with it.

The operator now answers by key K_{xi} and handles the call as in Fig. 6, the device of Fig. 20, controlling the relays S S' as hereinbefore discussed, and those relays in turn controlling the device of Fig. 7, as hereinbefore discussed.

Upon the completion of the cycle of the wheel Q^{25} , the battery potential is broken from relay H, and by release of its armature 643 the relay T is unlocked. By the unlocking of relay T, the clutch magnet 625 is deenergized and shaft 624 moves its wipers out of contact with the main trunk just served. Upon the conclusion of the conversation the hanging up of the telephone at 606 breaks the circuit for current flowing through relay D, and by the release of its armatures the battery B is closed over wires 621, 623 to wires 644-645 which, through contacts of relay F, are connected to wires 30x-31x. The deenergization of D deenergizes magnet 618 which operates its clutch to connect shaft 601 to the source of power, and the wipers thus are moved out of connection with the served line. The breaking of wiper 605 from contact 615 interrupts the current through relay D'. By

deenergization of D', F is deenergized, 65 which in turn breaks wires 644-645 from 30x-31x. The interval of battery connection to 30x-31x has restored to normal the switching mechanism of Fig. 7 as hereinbefore described, and all parts of the system 70 are again in normal condition in readiness for the next call.

Now the method of my invention may be fully comprehended. Taking a general view of the entire system as described and 75 which carries out the method of my invention, and recalling the outline of the same given at the beginning of this specification that method is seen to consist in the following: First selectively and automatically converging traffic units when initiated upon and automatically distributing the converged units among, correlated interchangeable connective agencies, (this being accomplished in this described embodiment of my 80 invention principally through the apparatus shown in Figs. 1 to 4 and 6); automatically distributing and referring said units at this stage through correlated interchangeable normally free secondary agencies to operators, (principally through the apparatus of Figs. 6 and 5); ascertaining the nature and destination of each unit, (which the operator does through the connection of the talking set Figs. 5 and 6); predetermining 90 the mechanical and electrical steps of the connecting agencies necessary to attain said destination by translating and setting up the whole expression of said designation in code form, (principally through the keys 100 and associated apparatus of Figs. 5 and 13 to 16 of this embodiment); causing automatic operation of the connective agencies in accordance with said code form without further volition or attention on the part 105 of the operator, (through the sending machine Q, Q', etc., of Fig. 5 and associated apparatus); and finally placing the traffic unit or completed connection under control through the connective agencies alone, and 110 automatically releasing the operator for the receipt and despatch of other units, (through the automatic disconnection of the apparatus of Figs. 5 and 6 from the traffic lines of Figs. 6 and 7, after the traffic unit 115 reaches its destination as described).

Any other form or forms of apparatus desired may be used to carry out the method of my invention as will be fully apparent upon an inspection of my aforementioned 120 copending applications. In addition to originating the method, I have originated a large number of systems and apparatuses by which it may be carried out. This method of handling telephone traffic may 125 be used in entirety or in parts most suitable to any given case, as my applications referred to and other art clearly show, and it

should be borne in mind that each partial use of the complete method of my invention constitutes in itself a complete whole when operatively so used. I prefer however that 5 the method be practised in its entirety since as is obvious, the results secured are vastly more efficient than when partial practice is carried on.

Having thus described my invention, what 10 I claim and desire to secure by Letters Patent is:—

1. The method of establishing variable conductive paths and directing telephone traffic therethrough which comprises the 15 following steps: (a) selectively converging incoming call units when initiated, upon and distributing the converged call units among, correlated interchangeable connective mechanisms; (b) selectively converging, 20 distributing, and referring said call units at this stage through correlated interchangeable normally free secondary mechanisms upon, among and to operators' positions; (c) translating and setting up the 25 whole expression of the designation of the destination of each call unit in a code form; and (d) causing operation of said connective mechanisms in accordance with said code designation, independently of further 30 volition or attention on the part of an operator.

2. The method of establishing variable conductive paths and directing telephone traffic therethrough which comprises the 35 following steps: (a) selectively converging incoming call units when initiated, upon and distributing the converged call units among, correlated interchangeable connective mechanisms; (b) selectively converging, 40 distributing, and referring said call units at this stage through correlated interchangeable normally free secondary mechanisms upon, among and to operators; (c) translating and setting up the whole expression of

the designation of the destination of each 45 call unit in a code form; (d) causing operation of said connective mechanisms in accordance with said code designation, independently of further volition or attention on the part of an operator; and (e) finally 50 placing the completed path for the call unit under control through the connective mechanisms alone, and entirely detaching the operator from any further connection with said call unit or its path of travel thus 55 established.

3. The method of establishing variable conductive paths and directing telephone traffic therethrough which comprises the following steps: (a) selectively converging incoming call units when initiated, upon and distributing the converged call units among, correlated interchangeable connective mechanisms; (b) selectively converging, 60 distributing, and referring said call units at this stage through correlated interchangeable normally free secondary mechanisms upon, among and to operators; (c) translating and setting up the whole expression of the designation of the destination of each call unit 65 in a code form; (d) causing said connective mechanisms to operate in accordance with the code designation thus determined; and (e) finally placing the selected and completed path of travel for the call unit under 70 control through the connective mechanisms alone, from the communicating stations, and detaching and locking out the operator from any further association or connection with said call unit or its path of travel thus 75 established.

In testimony whereof I affix my signature in presence of two witnesses.

EDWARD E. CLEMENT.
